UNITED STATES PATENT OFFICE.

CLARENCE W. FOX, OF SAUGUS, MASSACHUSETTS.

DESIGN FOR A HANDLE FOR ICE-PICKS.

SPECIFICATION forming part of Design No. 23,138, dated March 20, 1894.

Application filed February 20, 1894. Serial No. 500,914. Term of patent 7 years.

To all whom it may concern:

Be it known that I, CLARENCE W. FOX, a citizen of the United States, residing at Saugus, in the county of Essex and State of Massachusetts, have invented and produced a new and original Design for a Handle for Ice-Picks, of which the following is a specification, reference being made to the accompanying drawing, forming a part thereof.

The drawing shows in front elevation my newly designed handle for ice picks.

The leading feature of my design consists in a cylindrical shank or body portion *a*, having a triangular head or end portion *b*. The

cylindrical shank *a* is slightly enlarged at its 15 lower end, at *a'*, and at its upper end in forming the triangular head *b*, three flat faces *c* are presented.

I claim—

The design for a handle for ice picks, herein 20 shown and described.

In testimony whereof I have signed my name to this specification in the presence of two subscribing witnesses.

CLARENCE W. FOX.
